UNITED STATES PATENT OFFICE.

ROLF SELQUIST, OF PITTSBURGH, PENNSYLVANIA, ASSIGNOR TO PITTSBURGH GAGE & SUPPLY COMPANY, OF PITTSBURGH, PENNSYLVANIA, A CORPORATION OF PENNSYLVANIA.

WRINGER.

Application filed July 9, 1921. Serial No. 483,397.

To all whom it may concern:

Be it known that I, ROLF SELQUIST, a citizen of the United States, and a resident of Pittsburgh, in the county of Allegheny and State of Pennsylvania, have invented a new and useful Improvement in Wringers, of which the following is a specification.

This invention relates to wringers and particularly to that type used in connection with and mounted upon washing machines for wringing the clothes after the same have been washed.

It is the object of this invention to provide means to prevent further turning of the wringing rollers after the same have been choked by an abnormal accumulation or a bunching of articles passing between the same, or in the event that the articles be fed into the wringer at a rate above that for which the wringer is designed.

It is a further object to relieve the load upon the driving motor in the event of choking of the rolls, thus eliminating the danger of burning out the motor when an electric motor is employed.

Special objects of the invention are to provide a construction in which the mechanism for accomplishing the above mentioned objects is readily responsive regardless of the point along the rolls at which the choking occurs or at which the operator may be caught, which will be simple and easy to repair, which will be adapted for use in conjunction with various forms of well known release mechanisms for relieving the tension upon the rolls, and which may be adjusted to function under varying conditions by varying the tension of the ordinary tension means for the rolls.

Like reference characters denote corresponding elements throughout the several views of the drawings in which Fig. 1 is a vertical sectional view with parts in elevation of the preferred embodiment of my invention; and Fig. 2 is a transverse vertical sectional view taken on the line II-II of Fig. 1.

The preferred form embodying the invention comprises a main frame or housing 1 provided with the compartments 2 and 3 formed by the inwardly extending ribs 4 and 5 upon the interior of the housing. Extending substantially the full width of the housing are the wringer rolls 6 and 7, the upper roll 6 having extensions 8 and 8' pro-

jecting into the compartments 2 and 3 and the lower roll 7 being similarly provided with extensions 9 and 9'. Mounted upon the extensions 8 and 9 are the fixed pinions 10 and 11. The extension 9' is journaled in a recess 12 in the driving gear 13 and its shaft 13', a bushing 14 being provided for this purpose. The shaft 13' rests upon the fixed bearing block 15 supported by the pin or bolt 16 and the extension 9 is similarly positioned by the bearing block 17 and pin 18. The extension 8' on the upper roller has attached thereto pinion 19 normally meshing with the driving gear 13. Resting upon the extensions 8 and 8' are the floating bearing blocks 20, 20' supported with coil springs 21, 21', the tension of which may be adjusted by moving the cross bar 22 through the agency of the levers 23, 23', cross-head 24, stud shaft 25, and the adjusting shaft 26.

A well known form of release mechanism is illustrated at 27-28 to relieve the pressure between the rolls when desired. The details of the tension adjusting means and release mechanism form no part of the present invention and need not be described in detail.

A strut rod 29 extends across the bottom of the housing which may be used as a supporting means for any desired purpose.

In operation, the tension means being adjusted to exert the desired pressure between the rolls, power is applied to shaft 13 from any desired source which causes rotation of the driving gear 13 which through the pinion 19 rotates roll 6 and its attached pinion 10, which, in turn rotates pinion 11 and the lower roll 7, extension 9' of the lower roll turning freely in its bushing 14. Should an abnormal quantity of clothes be fed between the rolls or should a bunching of the same occur, or should the operator be caught between the rolls, so as to force the rolls away from each other a distance equal to or greater than the length of the teeth on the driving gear, as indicated by the dotted lines in Fig. 1, power will no longer be communicated to the roll 6 which will remain idle, and since roll 7 depends upon its connection with roll 6 for its movement, it too will remain idle until the articles separating the rolls are removed, at which time the spring 21 together with the weight of the parts will again engage pinion 19 and gear 13 for normal operation. This

2.

disengagement takes place automatically without any care on the part of the operator, and during the disengagement there is no tendency whatever for the rolls to turn thus drawing the articles further between them, which facilitates removal of the same. It also prevents choking of the rolls from throwing an abnormal load upon the motor driving the wringer thus preventing the 10 burning out of the electric motor which is the type usually employed.

It is to be noted that although the mechanism described is preferably used with some type of tensioning means for the rolls in 15 which a substantially uniform pressure is maintained throughout the extent of the rolls, for instance as illustrated in the drawings, yet the same is equally adapted for use in connection with many of the well known 20 types of tensioning devices and in no way interferes with the adjusting mechanism and release devices commonly employed. It is also noted that adjustment for varying the point at which this disengagement will 25 take place is made by simply increasing or decreasing the tension of the particular tensioning means employed.

It is thus seen that I have provided a device simple in construction, easily adjusted 30 to varying conditions of operation, automatic in action and one which will prevent damage to the operator, to the driving motor, and to the articles being wrung.

I claim:

- 35 1. A wringer comprising a frame, an upper roll having gears attached at opposite ends thereof, a driving gear meshing with a one of said gears, a lower roll having a gear attached at one end meshing with the 40 remaining gear on the upper roll, a shaft projecting from the opposite end of the lower roll, said driving gear being provided with a recess in which said shaft is journaled and supported, the upper roll being resiliently 45 mounted for bodily movement and capable of movement a sufficient extent to disengage

the teeth of the driving gear from its co-operating gear on the upper roll, whereby separation of the rolls a predetermined amount will prevent rotation of the rolls 50 and remove the load from the driving means.

2. A wringer comprising a frame, a lower roll, fixed bearings in said frame, a driving gear journaled in one of said bearings, said 55 roll having a shaft journaled at one end in the other of said bearings and journaled at its other end in a recess in said driving gear, a pinion attached to the first mentioned end thereof, an upper roll cooperating with said 60 lower roll and having pinions fixed at its opposite ends meshing respectively with the first mentioned pinion and the driving gear, movable bearings for said upper roll capable of movement a sufficient extent to permit 65 disengagement of the driving gear and its cooperating pinion and tensioning means for said movable bearings urging them towards the fixed bearings.

3. A wringer comprising a frame, a lower 70 roll, fixed bearings in said frame, a driving gear journaled in one of said bearings, said roll having a shaft journaled at one end in the other of said bearings and journaled at 75 its other end in a recess in said driving gear, a pinion attached to the first mentioned end thereof, an upper roll cooperating with said lower roll and having pinions fixed at its opposite ends meshing respectively with the first mentioned pinion and the driving gear, movable bearings for said upper roll, coiled compression springs disposed between and adjustably fixed abutment and said movable bearings, the spring associated with the movable bearing adjacent the driving gear being capable of displacement under compression a sufficient extent to permit disengagement of the driving gear and its cooperating pinion. 85

In testimony whereof, I sign my name.

ROLF SELQUIST.
